UNITED STATES PATENT OFFICE.

JOHN H. RING, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A PLATTER OR SIMILAR ARTICLE.

53,611.

Specification for Design.

Patented July 15, 1919.

Application filed April 5, 1919. Serial No. 287,844. Term of patent 3½ years.

To all whom it may concern:

Be it known that I, JOHN H. RING, a citizen of the United States, residing at Providence, in the county of Providence and State of Rhode Island, have invented a new, original, and ornamental Design for Platters or Similar Articles, of which the following is a specification, reference being had to the accompanying drawing, forming part thereof.

The figure in the drawing is a plan view of a platter, showing my design.

I claim—

The ornamental design for a platter or similar article, as shown.

JOHN H. RING.

Witnesses:

JOHN S. HOLBROOK,
FORD MORAN.
